UNITED STATES PATENT OFFICE.

ALOYSIUS A. ROESCH, OF ANDOVER, MASSACHUSETTS.

EXPANDING TOOL.

Application filed September 20, 1926. Serial No. 136,605.

This invention relates to the class of expanding tools and devices.

It has been found necessary in associating the spindle body or head of the knuckle of a front axle assemblage with the knuckle ends of the axle to file or cut bushings, to obtain the proper operative association of the spindle body or head with the knuckle ends, and to otherwise true up or reface portions of the spindle body in obtaining such association of the spindle body. It has been discovered that by separating the knuckle ends of the axle, that the spindle body or head may be then associated with the knuckle ends without requiring the truing or facing of portions of the spindle body or the filing of bushings or the provision of washers or the like.

It is, therefore, the principal object of the present invention to provide a device capable of being used for fitting a spindle body or head of the knuckle of a front axle, between the knuckle ends of the axle, so as to obviate the truing, or refacing of portions of the spindle body or head, or the facing of either top or bottom of the spindle body or head newly rebushed, with the further end in view of saving time and labor in carrying out the assemblage of the spindle body or head.

With the foregoing, other objects of the invention will appear from the embodiment of the invention, which by way of example, is described in the following specification and illustrated in the accompanying drawings; in which:

Figure 1 is a sectional view through the tool of the present invention, parts being shown in elevation and the tool being shown in use ready for manipulation to spread the knuckle ends of a front axle, such as is included in the running gear of an automobile.

Figure 2 is an elevation illustrating the active condition of the tool, and showing the knuckle ends of the axle spread to a new relationship.

Referring now more particularly to the views of the drawing, it will be apparent, that the tool or device of the present invention includes two main parts, a part 10 and a part 11. The part 10 is provided with a socket 12 which is capable of accommodating a suitable rod or bar 13 for applying a pulling or lifting force to the part 10. The part 10 is also provided with a cam portion 14 having a hole 15 therein which accommo-

dates a pin 16. The pin 16 is removable from the hole 15. The part 10 also includes a recess 17 one wall of which is curved or rounded so as to provide a cam portion 18. The side wall portions 19 of the recess 17 carry a pivot pin 20. The part 11 is cylindrical for a portion of its length, and has a flat portion 21. The flat portion 21 has a hole 22 therein which is larger in diameter than the diameter of the pin 20. The said flat portion 21 is also rounded as at 23 to provide a cam portion at one end of the part 11 adjacent the hole 22. The part 11 at the end opposite to the flat portion is cut to provide faces 24 and 25 which are relatively angularly disposed, the face 25 being substantially in a plane at right angles to the longitudinal axis of the part 11. The end of the part 11 opposite to the flat portion 21 has a hole 26 for the reception of a pin 27. The pin 27 is removable from the hole 26. The part 10 is in the nature of a fulcrum whereas, the part 11 is in the nature of a thrust lever. The pin 20 of the part 10 extends through the hole 22 in the flat portion 21. The cam portion 23 of the part 11 is in contact with the cam portion 18 of the part 10, and under this condition the pin 20 will be located concentrically with the hole 22 to provide a loose connection, so that no strain will come directly on the pin 20 when the tool is in use.

It has been found that a tool constructed in the manner herein above described serves adequately for spreading apart the knuckle ends of the front axle of the running gear on an automobile. It is to be understood that no limitation is necessarily made to such particular use. Referring now to Figure 1 it will be apparent that there has been illustrated a portion of a front axle of an automobile having the usual knuckle ends 28 between which are arranged the usual spindle body or head by virtue of the employment of a king or head bolt whose opposite ends extend respectively in holes 29 in the ends 28. By arranging the free end of the part 11, and the cam portion 14 of the part 10 respectively in engagement with the inner faces of the knuckle ends 28, with the pins 16 and 27 respectively in the holes 29, the part 10 then being manipulated by applying a lifting force thereto by virtue of the bar 13, will cause the knuckle ends 28 to spread apart. The knuckle ends 28 may be spread apart to a predetermined degree to accom-

modate the spindle body or head of the knuckle which has been newly rebushed without requiring the same to be faced either at the top or the bottom. It will at once be apparent that by providing the cam portion 14 on the part 10 and by providing the angularly disposed faces 24 and 25 on the part 11 that the desired rocking movement of the parts may be had and will insure the proper bending action of the tool. It will also be apparent that the pins 16 and 27 serve to properly locate the tool with respect to the knuckle ends 28, and prevent the displacement of the tool during the expanding or spreading operation. As the part 10 is being moved in the spreading operation, there comes a time when one side of the flat portion 21 comes into contact with the wall 30 of the recess 17, which wall 30 acts as a means for limiting the pivotal movement of the part 10 with respect to the part 11 in one direction. When the flat portion of the part 11 is confronted by the wall 30 the parts 10 and 11 will assume the relationship shown in Figure 2 in which a maximum spread will have been obtained, and the knuckle ends 28 will have been moved to a predetermined and correct relationship to accommodate therebetween the spindle body or head.

I claim:

1. An expanding tool comprising a fulcrum part having an arm, a thrust part, and

means loosely connecting said parts together, portions of said parts coacting with each other in the movement of one part to obtain a change in the relative angular disposition of said parts.

2. An expanding tool comprising a fulcrum part having an arm, a thrust part, means loosely connecting said parts together, portions of said parts coacting with each other in the movement of one part to obtain a change in the relative angular disposition of said parts, and means limiting the movement of one part with respect to the other.

3. An expanding tool comprising a pair of cooperative work engaging members, lever means for effecting the relative movement of said work engaging members, and a removable locating pin carried by each of said work engaging members.

4. An expanding device of the character described comprising work engaging parts, the said parts being associated with each other for pivotal movement, the association of the parts being effected by virtue of a pin which extends through portions of one of the parts and a hole in the other part, said hole being larger in diameter than the diameter of the pin, and a rounded portion on one part coacting with a rounded portion on the other part.

ALOYSIUS A. ROESCH.
